Application April 28, 1933, Serial No. 668,305

1 Claim. (Cl. 175—359)

This invention relates to articles and more particularly to electrical apparatus.

An object of the invention is to provide assembled articles for use in electrical apparatus which are simple to make, efficient in use and of greatly increased compactness and lessened bulk.

With this and other objects in view one embodiment of the invention contemplates the impressing upon both sides of a sheet of suitably prepared cellophane or other lamina of appropriate dielectric material of the design or trace of a spiral coil or other desired electrical member in a graphite ink or other conducting medium. The two printed traces extend to a common point at one of the principal edges of the sheet or to a common point at the edge of a preformed perforation in the sheet. The traces are then coated with copper or other conductor substance and the gap between the two traces is bridged by the coating process although there is no contact between the traces. The resulting dielectric sheets bearing the continuous conducting members thus formed thereon may then be assembled singly or in groups, by interfolding or otherwise into completed articles.

Other objects and characteristic features will appear from the following detailed description of one embodiment of the invention taken in connection with the accompanying drawing in which the same reference numerals are applied to identical parts in the several figures and in which

Fig. 1 is a diagrammatic view of a section of coil constructed in accordance with the invention and shown before folding;

Fig. 2 is a similar perspective view thereof partly folded;

Fig. 3 is a diagrammatic view in perspective of a finished coil;

Fig. 4 is a view in section on the line 4—4 of Fig. 1 of the dielectric lamina before treatment;

Fig. 5 is a similar view showing the conductive ink in place;

Fig. 6 is a similar view after the electroplating operation; and

Fig. 7 is a view in perspective of an intercalary insulating lamina.

As herein disclosed a thin lamina or sheet 10 of cellophane or other dielectric material may be prepared for use as the base or carrier of a conductive trace 12 by being precreased for subsequent folding as at 13 and further by being provided, e. g. by punching, with perforations 14 which will subsequently be aligned to receive a core 15 if desired. The lamina is herein shown

as comprising five connected panels but may be of any continuous length as desired, and in practice will preferably have many more such panels in connected sequence. The perforation 14 may further be formed to have a notch 16 at one point of one edge.

Upon the lamina thus prepared is then deposited a trace or outline 11 of the desired conductor in a conducting medium. This may be most simply done by printing the trace with an ink containing graphite or a metallic pigment in an adhesive medium, or the trace may be applied by stencilling, or by means of a transfer roller, or by decalcomania, or by any other satisfactory means. The trace is applied as indicated in the drawing to both sides of the lamina and on any one given panel will, in general, form two disconnected sections both ending at the same point of the perforation 14 as indicated at 16. It will be understood that the dimensions of the lamina, trace and conductor are strongly exaggerated transversely to the lamina in Figs. 4, 5 and 6 to clarify the structure.

The trace upon each side of any given panel will, in general, be continuous with the trace upon the same side of one neighboring panel as indicated at 17, the trace passing without solution of continuity across the creases 13. Further to ensure against rupture of electrical continuity at the creases 13 when the lamina is subsequently folded, it may in some cases be desirable to widen the trace across and in the immediate vicinity of the creases 13 as also indicated at 17. The trace may also be provided with enlarged portions as at 18 at its extremities to afford convenient contacts for ultimate attachment of leads 19 to the finished coil.

The lamina with the electrically conductive trace thereon is then immersed in an appropriate electroplating bath and the various sections of the trace are made simultaneous negative electrodes so that deposition of metal takes place simultaneously upon each pair of trace sections which terminate at any one common point 16 of the perimeter of a perforation 14. It is found that deposition proceeds more rapidly at the very narrow neighboring edges 20 (Fig. 5) than for example upon the broad faces 21 and 22 of the two sections of the trace. The principal result of this effect is that the metallic deposit 12 grows across the edge of the lamina at the point 16 as shown in Fig. 6 and thus unites the two sections of the metallic deposit on the two sides of the lamina into one continuous, jointless, homogeneous conductor.

The lamina is removed from the electroplating apparatus when a sufficient mass of conductor has been deposited thereon and is subjected to such washing and drying processes as may be necessary or desirable.

The conductor bearing lamina thus prepared may then be assembled with a similar creased and perforated but otherwise untreated, i. e. conductorless, lamina 23 applied to each face thereof 10 and the three laminae folded together accordion fashion on the creases 13, thus intercalating a double insulating layer of conductorless dielectric between each two consecutive panels of the conductor bearing sheet. The whole may then be 15 compressed, a core 15 inserted and terminal leads 18 attached to produce a finished coil as shown in Fig. 3. Or a single lamina 23 may be intercalated interfolding it with the lamina 10 with the folds of each lying at right angles to those 20 of the other and embracing the upper and lower edges alternately of successive panels of the other, thus interposing only one thickness of insulation between consecutive conductor bearing panels.

As herein disclosed the invention is shown embodied in a self-inductive coil. It is evident that the self inductiveness depends only upon the disposition or directions of turn of the conductor spiral sections upon consecutive panels and the coil could equally well be non-self inductive. So 25 also the drawing shows conductor spirals of one turn only for simplicity and clearness, but self-evidently the spiral on each panel is limited as 30

to number of turns only by the relative dimensions of its parts. Indeed it is not essential to the invention that the completed structure be a coil at all. The invention applies to many possible arrangements in which a pair of electrically conducting members are separated by a dielectric member except for conductive connection across the dielectric at substantially small portions thereof. The embodiment herein disclosed is illustrative merely and may be departed from and modified in many ways without departing from the spirit and scope of the invention as pointed out in and limited only by the appended claim. 5

What is claimed is:

As a new article of manufacture, a lamina of 15 dielectric material comprising a hinged sequence of panels folded together, an insulating sheet disposed between two consecutive panels, a narrow band of conductive material disposed upon each face of each of the two consecutive panels so that 20 each of the two bands upon one of the said panels extends to a common point on an edge of the panel and so that one band upon one of the two panels is continuous with one band upon the other panel on the same side thereof, and a conductive 25 coating upon the four bands and continuous on both sides and across an edge of the lamina at each of the two common point each such band and coating being enlarged in width where they cross a hinge between consecutive panels. 30
